UNITED STATES PATENT OFFICE.

JOSEPH MELZER, OF CLEVELAND, OHIO, ASSIGNOR OF TWO-THIRDS TO
FREDERICK HAFFNER AND MARTIN KOCH, OF SAME PLACE.

COMBINED ELECTRIC-ARC LAMP AND FAN.

SPECIFICATION forming part of Letters Patent No. 623,801, dated April 25, 1899.

Application filed October 27, 1898. Serial No. 694,715. (No model.)

To all whom it may concern:

Be it known that I, JOSEPH MELZER, a citizen of the United States, residing at Cleveland, in the county of Cuyahoga and State of

5 Ohio, have invented new and useful Improvements in a Combined Electric-Arc Lamp and Fan, of which the following is a specification.

My invention relates to improvements in combined electric-arc lamps and fans, and 10 pertains to an electric lamp provided with a surrounding motor for driving, preferably, a fan, all of which will be fully described hereinafter and particularly pointed out in the claims.

15 The primary object of my invention is to provide a combined electric lamp and electric motor, the motor preferably constructed to drive a fan, whereby a lamp and a fan are carried by the same hanger or support.

20 Another object of my present invention is to provide an electric-lamp hanger with a motor surrounding the carbon tube or hanger and the field and armature of the motor supported thereby, whereby a lamp and fan are 25 combined in one to be used separately or together, as desired.

Another object of my invention is to provide an electric lamp with a surrounding motor-field supported thereby and a motor-30 armature track also supported by the hanger, the motor-armature adapted to receive fan arms, whereby a combined fan and lamp or lamp and motor is provided and combined.

35 A further object of my invention is to provide a combined lamp and motor and a switch and electric connections between the switch, the motor, and the lamp, the switch so constructed that either the lamp or the fan may be used alone or both at the same time, as 40 may be desired.

In the accompanying drawings, Figure 1 is a vertical central sectional view of a combined arc-lamp and motor embodying my invention.

Fig. 2 is a similar view with parts of the lamp 45 and hanger omitted, showing a modification in the bearing for the motor-armature. Fig.

3 is a detached enlarged view of the switch-lever. Fig. 4 is a diagrammatical view showing the switch and electric connections be-50 tween the switch, the motor, and the lamp.

Fig. 5 is an enlarged sectional view of a portion of the adjusting member for primarily adjusting the limit of downward movement of the upper carbon of the lamp.

Referring now to the drawings, 1 indicates 55 a lamp hanger or support, and 2 a tube connected therewith and depending therefrom, carrying at its lower end a plate or disk 3. Surrounding the lower portion of this tube 2 is the winding 4, forming the magnet of a 60 solenoid, the tube 2 at its lower portion forming the usual hollow core of the solenoid. Surrounding the upper portion of the tube 2 is the usual rheostat or resistance for the solenoid 4. Situated within the tube 2, at its 65 lower portion, and surrounded by the solenoid is a brass tube 6, carrying at its lower end an iron tube 7, which is the armature of the solenoid. The lower end of the tube 2 is spread out or enlarged, as shown at 8, to form an 70 opening sufficiently large to receive the armature 7 and a spring 9 thereabove. The spring has its upper end engaging the upper end of the enlarged portion 8 of the tube 2 and its lower end engaging the upper end of 75 the armature 7, whereby the spring 9 normally forces the armature downward. The tube 6 receives the upper carbon 10, which is adapted under normal conditions to move freely therethrough. The operation, construction, and 80 arrangement of a carbon-feeding mechanism will be described hereinafter.

A depending tube 11 has its upper end turned outward, as shown at 12, and this upper portion of the tube 11 is suitably clamped 85 to the plate 3, an insulating material 14 being placed therebetween to insulate the tube 11 from the plate 3. Screwed within the lower end of the tube 11 is the lamp-globe socket 15, adapted to receive the screw-threaded socket 16 of the globe 17. The lower end of this globe 17 is provided with a screw-threaded socket 18, adapted to receive a screw-threaded plug 19, and this screw-threaded plug 19 is provided with a carbon-90 socket 20 for receiving and supporting the lower carbon 21. A wire 22 has its upper end electrically connected in any suitable manner with the globe-socket 16 and its lower end similarly connected with the metallic 100

socket 20 at the lower end of the globe, by means of which a current is carried to the lower carbon 21. A cup-shaped motor-support 25 has a screw-threaded central opening 26, which screws externally upon the lower end of the tube 11 and is supported thereby. The tube 11 in turn is supported by the plate 3 and the plate in turn by the tube 2, which is supported by the hanger 1, whereby the motor-support is held by the lamp-hanger. The side or vertical wall 27 of the cup-shaped support 25 is provided with the motor-field 28, which is arranged in series. An annular motor-armature 29 is arranged, preferably, in series upon a ring 30, the said ring 30 constructed with the portion 31 to receive the windings of the armature and with an upwardly-extending annular flange 32, which carries the commutator 33. Supported by the plate 3 are the commutator-brush supports 34. I here show the commutator-brushes consisting of spring-actuated copper pencils or rods 35, which engage the commutator 33, the commutator-brushes being electrically connected in the usual or any desired manner for receiving the current from the main line.

In Fig. 1 I show the preferred form of bearings for the motor-armature, which is in the form of a ball-bearing, the bottom of the cup-shaped support 25 being provided with a ball-race 37 and the ring 30 with a ball-race 38, the balls 39 being situated therebetween and serving to hold the armature in position as it rotates around the lamp-socket. Projecting from and supported by the ring 30 are a plurality of arms 40, which are U-shaped in side elevation, as shown, having at their outer ends horizontally-projecting sockets 41, adapted to receive the fan-arms 42.

It will be noted that the motor-field 28 is situated outside of the motor-armatures, and preferably in this form, though it will be readily conceived that this arrangement may be reversed, the main object being the supporting of the motor-field and armature by the lamp and surrounding it, whereby a combined lamp and motor are provided, the motor preferably for driving a fan.

The plate 3 carries the projecting contacts 45, and the plate 46 at the top of the solenoid carries an adjustable screw-threaded rod 47, insulated from the plate 46 and through which electrical connection is made through the contact 48, which passes between the contacts 45. This construction is for the purpose of having the contact 48 between the contacts 45 when the plate 3 has been screwed to its normal position upon the lower end of the tube 2.

The mechanism for feeding the carbon consists of the solenoid 4, its armature 7, the spring 9, and a spring depending arm 50, which has its upper end attached in any suitable manner to the brass tube 6 and its lower portion extending along parallel with and outside of the armature 7 and its lower end pro-

vided with an inwardly-projecting clutch portion 51, adapted to engage the carbon 10 below the armature. This spring-arm 50 is provided with an iron portion 53, which forms an armature adapted to be attracted by the solenoid-armature 7 when the latter is magnetized. In operation when the current is weakened the arm 50 will spring outward and release the carbon, permitting it to drop, and when the carbon has dropped and the current sufficiently strong the armature 7 will immediately be drawn upward, and at the same time the arm 50 is attracted by the armature 7, causing its clutching portion 51 to engage the carbon and to thereby draw the carbon up against the tension of the spring 9. The tension of the spring 9 is such as to hold the carbon at a proper point for a proper arc, and thus the carbon is fed as desired. The amount of downward movement permitted the armature 7 is regulated by the rod 55, which has its lower end passing through the plate 3 and turned inward under the armature, as shown. The upper end of the rod 55 passes through a tube 56, carried by the plate 46, and its extremity is screw-threaded to receive a thumb-nut 58, whereby it may be raised and lowered for regulating in the first instance the armature fall. The tube 56, as illustrated in Fig. 5, is provided with a platinum screw 59, engaging a groove 60, formed in the rod 55 and through which electrical contact is made, as will be readily understood by those skilled in the art. The object of the groove is to hold the rod against any turning or lateral movement.

The switch-lever *h* is pivoted to the under side of the cup-shaped motor-support 25, as illustrated in Fig. 1, and in Fig. 3 the specific construction of this lever is shown. This switch-lever is provided with the insulated spring-contact *f*, having two arms, as illustrated, and adapted to engage the plates *c*, which are insulated one from the other and also from the switch-plate 62. The lever is also provided with a spring-actuated contact *m* and with a second contact 63. Also carried by the plate 62 are the contact-points *g*, *e*, and *s*.

The electrical connections will now be described in a description of the operation of the switch for either throwing in the circuit the lamp, or the fan alone, or both. When the fan alone is thrown in, the lever *h* is moved to carry the contacts *f* in engagement with the contacts *c*, thus making electrical connection between these contacts, and the current is then from the main line to the wire *a*, *b*, contacts *c* and *f*, and the wire *d* to the motor and *p* and *j* to the other pole of the main line. When the lamp alone is to be operated, the lever *h* is moved to carry the contact 63 to the contact *e*, and the current passes through *a*, lever *h*, contact *e*, wire *i* to the clutch, through the carbons, and to the wire *j*. When both the lamp and fan are in operation, the lever *h* is moved still farther

in the direction indicated by arrow and the contact *f* in engagement with the contacts *c*, the contact *m* in engagement with the contact *g*, and the contact *h* in engagement with the contact *s*, when both the fan and motor circuits will be closed, as will be readily understood.

My invention is especially intended for indoor service, whereby a lamp and a fan may be combined in one and either or both used, as desired. In the winter season, when the fan is not in service, the fan-arms, if desired, may be detached from the motor-armature arms 40 or they may be left thereon, as desired.

Having thus described my invention, what I claim, and desire to secure by Letters Patent, is—

1. A combined arc-lamp and fan comprising a lamp-hanger having a carbon-tube, a cup-shaped motor-field support having a central opening, a depending flange having its upper end supported by the carbon-tube and its lower end connected within the said opening of the cup-shaped motor-field support, a vertically-movable carbon in said tube, a mechanism for adjusting the carbon vertically, a lower carbon support, a lower carbon supported thereby, an annular armature within the cup-shaped support, a bearing between the cup-shaped support and the annular armature, fan-support brackets carried by the armature, and electrical connections for the motor and the carbon, substantially as described.

2. A combined electric lamp and fan comprising a lamp support or hanger, a cup-shaped motor-field support carrying an annular motor-field and having a central opening, an upwardly-projecting flange connected to the wall of said opening at its lower end and at its upper end connected with the lamp-hanger, a globe-socket within the said tube, an annular armature surrounding the said tube and within the motor-field, a bearing for the armature carried by the cup-shaped support, and electrical connections for the motor and the electric carbon or filament, substantially as described.

3. A combined lamp and motor comprising an electric-lamp mechanism, a cup-shaped motor-field support carrying the motor-field on its inner vertical side, the bottom of the cup-shaped support provided with an opening through which the electric-lamp mechanism passes, an annular motor-armature surrounding the said opening and within the said field, the bottom of the cup-shaped sup-

port and the motor-armature provided with annular bearing-surfaces, substantially as described.

60

4. A combined electric lamp and fan comprising a lamp or fan hanger, a cup-shaped motor-field support having a motor-field on the inner side of its vertical wall, the bottom of the cup-shaped support having a central opening, a flange secured in said opening and projecting upward with its upper end attached to the lamp or fan hanger, the bottom of the cup-shaped support having an annular bearing-race, and the motor-armature having a coacting annular bearing-race, substantially as described.

65

5. An electric lamp comprising a solenoid, a hollow armature therefor, a carbon passing through the said solenoid, a spring-arm carried by and within the armature, and adapted to engage the carbon, the spring-arm carrying a magnet between the carbon and the inner wall of the armature and adapted to be attracted by the solenoid-armature, and an electric connection therefor, substantially as described.

75

6. An electric lamp comprising a solenoid, an armature therefor receiving a carbon, a clutch mechanism, a support for the armature limiting its downward movement, the support being vertically adjustable and having a longitudinal groove, and a platinum point engaging said screw and forming electrical connection, substantially as described.

80

7. In an electric-arc light, the combination of a globe-supporting socket in an electric circuit, a globe carrying an open socket at its upper end adapted to be detachably connected with said supporting-socket and through which the upper carbon freely passes, a carbon-socket at the lower end of the globe, and an electric connection within the globe having its end directly connected respectively with the sockets at the upper and lower ends of said globes, whereby the globe itself carries all connections necessary to complete the circuit when attached to the said supporting-socket, and can be detached without disturbing the connection, substantially as described.

95

In testimony whereof I have hereunto set my hand in the presence of two subscribing witnesses.

JOSEPH MELZER.
